UNITED STATES PATENT OFFICE.

ERNEST F. PFLUEGER, OF AKRON, OHIO.

ROSETTE FOR HARNESS.

SPECIFICATION forming part of Letters Patent No. 339,926, dated April 13, 1886.

Application filed December 20, 1885. Serial No. 187,174. (No model.)

To all whom it may concern:

Be it known that I, ERNEST F. PFLUEGER, of Akron, in the county of Summit and State of Ohio, have invented a new and useful Improvement in Rosettes for Harness, of which the following is a description.

Figure 1 is a central section; Fig. 4, a front view, and Figs. 2 and 3 are sectional views of modified forms.

10 My invention relates to rosettes for harness; and it consists in means for securing the holding-loop to the rosette-frame more strongly, as hereinafter described.

In the drawings, A represents the back 15 plate of the rosette, which plate is of disk shape, and has its outer edge turned inwardly, to embrace and hold the edges of the glass plate B in front.

C is the loop which gives passage to one of 20 the straps of the harness and serves to connect the rosette to the same. These loops have heretofore been extended through perforations in the back plate and provided with collars and riveted, as in my prior Patent 25 No. 303,318; or their ends have been extended through such perforations and bent over; or their ends have been soldered to the outside of the back plate.

In my present invention, after punching the 30 holes I countersink the back plate on the inside by means of a die, which produces a hollow on the inside and a bulged projection, a, on the outside, and then after the ends of the loop are passed through the holes they are 35 embedded in a solid filling of solder, b, which flows around the same in the hollow and fills it up flush and smooth, thus making a solid connection between the back plate and loop, which is stronger than the other parts of the 40 frame.

In countersinking the back plate I may 45 punch with the die simply a countersink of conical form around each hole, and then flow the solder in this conical space around the ends of the loop and on the inside of the back plate, as in Fig. 1; or I may, as in Fig. 2, de-

press a trough-shaped countersink, a', between the holes, and after passing the ends of the loop through the holes bend their ends inwardly at right angles toward each other 50 until their ends lie flat in said trough, and the space around which on the inside is then filled up flush with solder; or I may depress from the holes outwardly to the periphery of the back plate two small trough-shaped indentations, a'', as in Fig. 3, and bend the ends of the loop at right angles outwardly, so that they shall lie in said troughs and be filled in like manner with solder. If desired, the loop may, where it rests in the holes of the back 55 plate, have a shoulder turned on the same to keep the loop from being forced inwardly.

For ornamenting the rosette, I paint, print, or otherwise affix a figure or letter on the back of the glass plate, and then over the whole of 60 the back side of the glass I paint with a frosted gilding of metal powder, as in Fig. 4, which gives a very handsome finish that is fully protected, and which may be used alone without a figure or letter, or be used as a background 65 for the same. I may, however, in connection with the first feature of my invention use a polished or embossed metal plate in rear of the glass instead of the frosted gilding.

Having thus described my invention, what I 70 claim as new is—

A rosette for harness having its back plate 75 perforated to receive the loop ends, and countersunk or punched outwardly, in combination with the loop having its ends extended through said holes and resting in said countersunk space, and a filling of solder flowed around the ends of the loop and filling the countersink, substantially as described.

The above specification of my invention 80 signed by me in the presence of two subscribing witnesses.

ERNEST F. PFLUEGER.
